ATTORNEY.

UNITED STATES PATENT OFFICE.

EARLE H. FRAZIER, OF DENVER, COLORADO.

DESIGN FOR A MOTOMETER LIGHT FOR AUTOMOBILES.

60,786.

Specification for Design. Patented Apr. 11, 1922.

Application filed July 23, 1921. Serial No. 487,191. Term of patent 3½ years.

To all whom it may concern:

Be it known that I, EARLE H. FRAZIER, a citizen of the United States, residing at Denver, in the county of Denver and State of Colorado, have invented a new, original, and ornamental Design for Motometer Lights for Automobiles, of which the following is a specification, reference being had to the accompanying drawing, forming part thereof.

The figure is a perspective side view of a motometer light for automobiles showing my new design.

I claim:

The ornamental design for a motometer light for automobiles, as shown.

In testimony whereof I have affixed my signature.

EARLE H. FRAZIER.
